UNITED STATES PATENT OFFICE.

JAMES BLACK AND JAMES FRAME, OF GLASGOW, SCOTLAND.

LOCOMOTIVE FIRE-BOX.

1,119,490.

Specification of Letters Patent.

Patented Dec. 1, 1914.

Application filed March 7, 1914. Serial No. 823,190.

To all whom it may concern:

Be it known that we, JAMES BLACK and JAMES FRAME, subjects of the King of Great Britain, residing at Langside, Glasgow, Scotland, and Cathcart, Glasgow, Scotland, respectively, have invented certain new and useful Improvements in Locomotive Fire-Boxes, of which the following is a specification.

10 This invention relates to fire boxes of locomotives of the type having a firing chamber and a combustion chamber separated from one another by means of a partition wall on which the brick arch rests. This 15 type of fire box, as usually constructed, has but a limited application in practice as it is only suitable for working with shallow fires, and, therefore, in coal or wood burning fire boxes, blow holes are liable to form in the 20 fuel bed and cause tube troubles while the shallowness of this type of box, with its limited volume, renders it unsuitable for burning oil fuel. Further, the high level of the fuel bed renders it necessary to fit the 25 brick arch at such a height above the bottom rows of flue tubes that the passage of the hot gases toward the flue tubes is impeded.

This invention has for its object, firstly, 30 to so construct the fire box that a suitable depth of firing chamber is provided above the fuel bed; secondly, to increase the size of the fire box so as to give the maximum heating surface, an increased fire box volume 35 above the fuel bed and a longer flame way from the fuel to the flue tubes; thirdly, to so construct and fit the fire box that, when necessary, it can, when of the wide bottom form, be readily disconnected and bodily 40 lowered down out of position without removing the back shell plate; and, fourthly, to introduce through the brick arch a secondary hot air supply either delivering to the top of the fire from the bottom of the 45 arch or to the combustion chamber from the top of the arch, or both.

The main feature of the invention is a special construction of foundation ring which, instead of being made as usual, is at 50 the sides made of a stepped or bent formation. The sides of the ring can extend from the tube and throat plates rearward and be

either horizontal or inclined for a portion of their length and then, at the front of the fuel bed, they bend downward either vertically or at an angle so that the ring at its rear portion, which may be either horizontal or inclined, is wholly or partly at a lower level than the front portion, such lower level being arranged to suit the fuel bed of the 60 firing chamber.

In order that the invention may be properly understood we have hereunto appended explanatory drawings which show, by way of example, different modes of carrying the 65 invention into effect.

Figure 1 shows, in vertical section, one mode of constructing a locomotive fire box in accordance with the invention. Fig. 1^a is a view of the foundation ring. Fig. 2 70 shows a similar construction of fire box but with a "mid-feather". Fig. 3 shows another form of the fire box and Fig. 4 shows a modification of the arrangement Fig. 3.

On the drawings, A represents the fire 75 box, B the boiler barrel, C the flue tubes, D the combustion chamber, E the firing chamber, F the brick arch, G the back water leg, and H the ash hopper.

The same reference letters wherever repeated indicate the same or similar parts.

In the construction shown at Fig. 1, the tube plate *a* and throat plate *b* are arranged at a suitable distance in advance of the fuel bed and the foundation ring *c* is, at *c*¹, declined to suit the fuel bed, the ring extending forward to the front of the fuel bed of the firing chamber where it is bent upward, at *c*², forming a support for the front wall *d* of the firing chamber, and, thereafter, it 85 is extended, at *c*³, horizontally or substantially horizontally to the tube and throat plates. The front furnace wall *d* is protected by fire bricks *e*, or equivalent, an air space *e*¹ being left between the wall and the 90 bricks *e*. The brick arch *F* extends from the top of this wall upward and toward the rear at a slight incline as shown and it serves to separate the combustion chamber from the firing chamber. The bottom of 100 the combustion chamber is constituted by the said arch *F* and also by a steel plate or casting *f* which may be a continuation of, or be fixed to, the plate *d* forming the front

furnace wall, this plate *f* being protected by a brick lining at *m*. A counter-weighted or a spring door *h* is provided to the hopper bottom *H* (see Figs. 2, 3, and 4) for the removal of ash deposited in the chamber.

It will be seen that, while the floor of the combustion chamber is retained at a level suitable for giving the hot gases free access to the bottom row of boiler tubes, the bottom of the firing chamber is wholly or partly, at a lower level, which is rendered possible by the stepped formation of the foundation ring.

The top of the front wall *d* and arch *F* and the position of the fuel bed are arranged as low as possible, thus providing for the largest possible volume in the fire box and the free passage of the hot gases toward the tubes.

The arch *F* may be made with a passage way *g* having ports *g*¹ leading to the bottom of the combustion chamber and ports *g*² leading to the top of the firing chamber, a secondary supply of air being admitted at *k* and passing upward between the brick work *e* and plate *d* to the passage way *g* and then through the ports *g*¹, *g*². As the bricks become white hot, the entering air becomes highly heated. Of course, there may be merely the ports *g*¹, or the ports *g*², instead of both sets of ports. The entering air may be regulated by a cock indicated at *i*.

As the whole fire box is carried on the foundation ring and is fitted in position in the usual way it is obvious that it can be bodily withdrawn without removing the back shell plate *j* or breaking any of the joints of the fire box itself.

In the construction shown at Fig. 2 the brick work *e* is replaced by an inclined "mid-feather" or transverse water chamber *l* communicating with the side water spaces of the fire box.

In the construction shown at Fig. 3, the foundation ring is made horizontal at *c*¹, vertically stepped at *c*² and horizontal at *c*³ while there is a vertical "mid-feather" *l*¹.

In the arrangement shown at Fig. 4 the foundation ring is horizontal at *c*⁴, declined at *c*¹, vertical at *c*², and horizontal at *c*³, and in this case a vertically arranged transverse water chamber *l*² is employed, this chamber being simply inserted in position and connected by piping with any desired part of the boiler or water tank.

Having now fully described our invention, what we claim and desire to secure by Letters Patent is:—

1. In a locomotive firebox having two chambers, a firing chamber and a combustion chamber, a foundation ring for both chambers and which from the level of the bottom of the front wall of the firing chamber is stepped vertically or substantially

vertically upward to the level of the floor 65 of the combustion chamber.

2. In a locomotive fire box divided into two chambers, a firing chamber and a combustion chamber, a foundation ring for both chambers and which extends downward 70 from its rear end and is then bent upward and thereafter continued forward horizontally or substantially horizontally.

3. In a locomotive fire box divided into two chambers, a firing chamber and a combustion chamber, a foundation ring for both chambers and which is declined from its rear 75 end and is then bent vertically upward and is thereafter continued forward horizontally.

4. A locomotive fire box divided into two chambers, a firing chamber and a combustion chamber, a foundation ring for both chambers and which is of a stepped formation at the sides thereof, and a front plate 85 carried by said foundation ring at the stepped part thereof.

5. A locomotive fire box divided into two chambers, a firing chamber and a combustion chamber, a foundation ring for both 90 chambers and which is of a stepped formation at the sides thereof, a front plate carried by said foundation ring at the stepped part thereof and brickwork in rear of said plate and forming the front of the firing 95 chamber.

6. A fire box divided into two chambers, a firing chamber and a combustion chamber, the combustion chamber being at a higher level than the firing chamber, said fire box 100 being carried on a foundation ring which is bent upward at the front of the firing chamber and is then continued forward so as to carry the bottom of the combustion chamber.

7. A locomotive fire box divided into two chambers, a firing chamber and a combustion chamber, the combustion chamber being at a higher level than the firing chamber, said fire box being carried on a foundation 110 ring which is bent upward at the front of the firing chamber and is then continued forward so as to carry the bottom of the combustion chamber, the part where the foundation ring is bent upward carrying 115 the front wall of the firing chamber.

8. A locomotive fire box divided into two chambers, a firing chamber and a combustion chamber, the combustion chamber being at a higher level than the firing chamber, said 120 fire box being carried on a foundation ring which is bent upward at the front of the firing chamber and is then continued forward so as to carry the bottom of the combustion chamber, the part where the foundation ring is bent upward carrying the front wall of the firing chamber and being protected by brickwork.

9. A locomotive fire box divided into two chambers, a firing chamber and a combustion chamber, the combustion chamber being at a higher level than the firing chamber, said fire box being carried on a foundation ring which is bent upward at the front of the firing chamber and is then continued forward so as to carry the bottom of the combustion chamber, the part where the foundation ring is bent upward carrying a plate forming the front wall of the firing chamber, brickwork in rear of said plate and an air space between said plate and the brickwork.
10. A locomotive fire box divided into two chambers, a firing chamber and a combustion chamber, the combustion chamber being at a higher level than the firing chamber, said fire box being carried on a foundation ring which is bent upward at the front of the firing chamber and is then continued forward so as to carry the bottom of the combustion chamber, the part where the foundation ring is bent upward carrying the front wall of the firing chamber, and an arch forming a partition between the firing chamber and the combustion chamber.
11. A locomotive fire box divided into two chambers, a firing chamber and a combustion chamber, the combustion chamber being at a higher level than the firing chamber, said fire box being carried on a foundation ring which is bent upward at the front of the firing chamber and is then continued forward so as to carry the bottom of the combustion chamber, a front wall in the firing chamber at the part where the foundation ring is bent upward, an arch projecting from said wall at an angle thereto said arch serving as a partition between the firing chamber and the combustion chamber and having passageways therein for air to pass into the firing chamber.
12. A locomotive fire box divided into two chambers, a firing chamber and a combustion chamber, the combustion chamber being at a higher level than the firing chamber, said fire box being carried on a foundation ring which is bent upward at the front of the firing chamber and is then continued forward so as to carry the bottom of the combustion chamber, a front wall in the firing chamber at the part where the foundation ring is bent upward, an arch projecting from said wall at an angle thereto, said arch serving as a partition between the firing chamber and the combustion chamber and having passageways therein for air to pass into the combustion chamber.
13. A locomotive fire box divided into two chambers, a firing chamber and a combustion chamber, the combustion chamber being at a higher level than the firing chamber, said fire box being carried on a foundation ring which is bent upward at the front of the firing chamber and is then continued forward so as to carry the bottom of the combustion chamber, a front wall in the firing chamber at the part where the foundation ring is bent upward, an arch projecting from said wall at an angle thereto, said arch serving as a partition between the firing chamber and the combustion chamber and having passageways therein for air to pass into the combustion chamber.
14. A locomotive fire box divided into two chambers, a firing chamber and a combustion chamber, the combustion chamber being at a higher level than the firing chamber, said fire box being carried on a foundation ring which is bent upward at the front of the firing chamber and is then continued forward so as to carry the bottom of the combustion chamber, a front wall in the firing chamber at the part where the foundation ring is bent upward, an arch projecting from said wall at an angle thereto, said arch serving as a partition between the firing chamber and the combustion chamber and having passageways therein for air admitted to the arch by a passageway in the front wall of the firing chamber.
15. A locomotive fire box divided into two chambers, a firing chamber and a combustion chamber, the combustion chamber being at a higher level than the firing chamber, said fire box being carried on a foundation ring which is bent upward at the front of the firing chamber and is then continued forward so as to carry the bottom of the combustion chamber, a front wall in the firing chamber at the part where the foundation ring is bent upward, an arch projecting from said wall at an angle thereto, said arch serving as a partition between the firing chamber and the combustion chamber and having passageways therein for air admitted to the arch by a passageway in the front wall of the firing chamber.
16. A locomotive fire box divided into two chambers, a firing chamber and a combustion chamber, the combustion chamber being at a higher level than the firing chamber, said fire box being carried on a foundation ring which is bent upward at the front of the firing chamber and is then continued forward so as to carry the bottom of the combustion chamber, the part where the foundation ring is bent upward carrying the front wall of the firing chamber, and means whereby air can be admitted through said front wall to either the combustion chamber or to the firing chamber.
17. A locomotive fire box divided into two chambers, a firing chamber and a combus-

tion chamber, a foundation ring for both chambers and which is of a stepped formation at the sides thereof, a front plate carried by said foundation ring at the stepped part thereof and refractory means for protecting said front plate, said refractory means forming the front wall of the firing chamber.
